PIPE-LINE BOOSTER

Russell Klemm, Ridgewood, N. J., assignor to De
Laval Steam Turbine Company, Trenton, N. J.,
a corporation of New Jersey

Application September 30, 1933, Serial No. 691,632

2 Claims. (Cl. 137—78)

This invention relates to a booster arrangement for a pipe line and more particularly an arrangement adapted for a pipe line for the transportation of gas involving the use of centrifugal compressors.

In transporting gas through long pipe lines centrifugal compressors driven by electric motors may be used to advantage, the centrifugal compressors being located within the pipe line. In

10 a pipe line several hundred miles long a large number of compressors may be used rather than one compressor at the beginning of the line, each compressor acting as a booster for the preceding one and substantially reducing the average pressure along the line to produce a given flow. For instance, the compression stations may be located such distances apart that the loss in pressure between the stations is, say, 100 pounds, while the maximum pressure in the line which

20 would occur at the outlet of each compressor might be of the order of 500 pounds. The entire pipe line is preferably under comparatively high pressure in order to keep down its size and in order to obtain a small compression ratio in the booster pumps involving only two or three stages in each centrifugal compressor. Assuming figures such as those indicated the friction loss between the compressor stations would be 100 pounds so that the inlet pressure of each compressor would be 400 pounds and the discharge pressure 500 pounds.

When a pipe line such as this is operating at full capacity all of the compressors may be in operation. When a reduced flow is taking place it is, of course, desirable to shut down one or more units on account of the lower friction loss in the piping at low capacities. It has been customary when shutting down a compressor to bypass the gas around the compressor by the use of an arrangement of piping and manually operated valves. This is done since a stationary compressor would offer such tortuous passages for the flow of gas that the losses would be of considerable magnitude, this being particularly true in the case of a multistage compressor.

In accordance with the invention there is provided an automatic bypass which requires no outside piping or manipulation of valves. The bypass in accordance with the invention is provided within a housing about the compressor, there being provided valve controlled openings which automatically at the proper time permit flow to take place.

55 The invention will be more fully understood from the following description read in conjunction with

the accompanying drawing in which the figure is a sectional view showing the portion of a pipe line adjacent a booster pump.

A housing 2 for the pump is made a part of the pipe line indicated at 4. Within this housing is located an electric motor 6 which drives the rotor of a centrifugal compressor having two stages 8 and 10. The first stage receives the gas at 12 and discharges into the passage 14 which delivers to the intake of the second stage 18 whence the compressed gas passes into the discharge passage 16 and then into a nozzle 18 carried by a diaphragm 20 extending transversely across the housing 2. The nozzle 18 is so formed as to reduce the velocity of the gas with a consequent increase in pressure; the net result being that the pressure on the discharge side is considerably larger than that on the intake side, the difference representing the average friction loss between the booster stations.

The diaphragm is provided with openings 22 furnished with seats for check valves 24 which open in the direction of flow through the line. Each check valve 24 is carried by a stem 26 sliding through a suitable guide and provided with 25 a head 28 to limit the opening movements of the valves. The housing 2 is spaced from the compressor casing somewhat more than is usual in order to provide an enlarged bypass which will not involve losses due to constriction. When the 30 compressor is operating all of the gas flowing through the pipe line will be handled by it, the excess pressure on the high side causing the check valves 24 to close and remain closed. By reason of the construction which is provided very little 35 pressure or velocity of flow is required to move the check valves to open or closed positions.

If the compressor is stopped then the pressure to the right of the diaphragm 20 will rise so as to force the check valves open. By providing a suitable number of these valve controlled openings there will be offered very little resistance to flow of gas past the diaphragm, the resistance being very much less than that which would be encountered if the gas were forced to flow through 45 the stationary compressor which, as will be clear from the drawing, involves tortuous passages in which friction losses will be very great.

If after a shutdown the compressor is restarted 50 there will be first produced by reason of the excess pressure on the left a flow of gas towards the right through the openings which will immediately produce a closure of the check valves.

It will be seen from the above that there is 55 provided a construction which requires no at-

tention in insuring a proper bypass for the gas whenever the compressor is shut down. Furthermore, the bypass is closed whenever the compressor is restarted. External pipe is entirely avoided and there need be no attendant present 5 in the booster stations to manipulate valves. The motor 6 may, of course, be remotely controlled or automatically controlled depending upon the conditions of flow.

It will be clear that the invention may be embodied in other modifications of construction 10 without departing from its scope as defined in the following claims.

What I claim and desire to protect by Letters Patent is:

15 1. In a pipe line for the transmission of elastic fluid at high pressures, a housing in said line provided with a transverse diaphragm having an opening therein, a driving motor and centrifugal pump within the housing arranged to produce a 20 flow through said opening, said opening being provided with an expanding nozzle whereby the pressure on the delivery side of the diaphragm substantially exceeds that on the opposite side, one or more auxiliary openings through said dia- 25 phragm, and means controlling said auxiliary

openings whereby when the pump is not operating flow takes place through the housing about said pump and through said auxiliary openings, said means comprising a check valve opening in the direction of by-pass flow.

2. In a pipe line for the transmission of elastic fluid at high pressures, a housing in said line provided with a transverse diaphragm having an opening therein, a driving motor and centrifugal pump within the housing arranged to produce a flow through said opening, said opening being provided with an expanding nozzle whereby the pressure on the delivery side of the diaphragm substantially exceeds that on the opposite side, one or more auxiliary openings through said diaphragm, and means controlling said auxiliary 15 openings whereby when the pump is not operating flow takes place through the housing about said pump and through said auxiliary openings, said means comprising a check valve opening in the direction of by-pass flow and arranged to be moved without other than frictional restraint by differences of pressure on opposite sides of said diaphragm. 20
